UNITED STATES PATENT OFFICE.

JACOB S. SHERMAN, OF CHICAGO, ILLINOIS.

DESIGN FOR A CONTAINER FOR CIGARS AND TOBACCO.

Application filed September 13, 1924. Serial No. 10,774. Term of patent 14 years.

To all whom it may concern:

Be it known that I, JACOB S. SHERMAN, a citizen of the United States, residing at Chicago, in the county of Cook and State of Illinois, have invented a new, original, and ornamental Design for Container for Cigars and Tobacco, of which the following is a specification, reference being had to the accompanying drawing, forming a part hereof.

In the illustration,
Fig. 1 is an elevational view of a container, showing my new design, and
Fig. 2 is a top view of same.

I claim:

The ornamental design for a container for cigars and tobacco, substantially as shown.

JACOB S. SHERMAN.
